PUMP STRUCTURE

Filed Sept. 27, 1928

UNITED STATES PATENT OFFICE

FREDERICK W. JOHNSON, OF EXCELSIOR, MINNESOTA

PUMP STRUCTURE

Application filed September 27, 1928. Serial No. 308,621.

This invention relates to pumps of the force and suction type.

It is an object of my invention to provide an extremely simple but highly efficient pump which is especially designed for pumping water containing considerable foreign material, such as mud, gravel and refuse.

It is a further object to provide a pump which will withstand extremely heavy wear and which is so constructed that the pumping chamber and valve chambers may be quickly and easily opened for the purpose of replacing or repairing parts and for examining the same.

Another object is to provide a force and suction pump which will permit relatively large pieces of foreign material to be easily pumped through the valve chambers without impedance and without damage to any of the parts.

More specifically it is an object of my invention to provide a pump having an elongated substantially horizontal body provided with a pair of valve chambers in which a durable and simple flap valve are angularly disposed permitting foreign material to be pumped without damage to the parts and a vertical pumping cylinder connected to the upper end of said body intermediately of said valve chambers, whereby said foreign material cannot enter and damage said pumping cylinder or the plunger therein.

These and other objects and advantages of the invention will be apparent from the following description made in connection with the accompanying drawings in which like reference characters refer to similar parts throughout the several views and in which:

Fig. 1 is a side elevation of an embodiment of the invention;

Fig. 2 is a cross section taken on the line 2—2 of Fig. 1, showing the top of the pump body in plan;

Fig. 3 is a vertical longitudinal section taken on the line 3—3 of Fig. 2;

Fig. 4 is a cross section taken on the line 4—4 of Fig. 3, showing the connection of the pumping cylinder with the body of the pump; and

Fig. 5 is a detail plan view of one of the flap valves detached.

As illustrated in the drawings, my improved pump comprises a substantially straight three-piece base or body, which may be of oblong cross section, said body comprising a central chamber 6 having parallel and inclined ends 6^a and 6^b respectively, an intake chamber 7 and an outlet chamber 8.

Intake chamber 7 has an inclined inner end adapted to register with the adjacent end of chamber 6 and has a substantially rectangular opening 7^a at said end, and a flange defining said opening constituting a seat for the intake valve.

The upper portion of intake chamber 7 has a depending inclined shoulder 7^b and the bottom of said chamber is slightly inclined to cause the water and material to drop slightly when entering chamber 6 from the intake chamber.

A simple and novel flap valve is interposed between the opposing ends of chamber 6 and intake chamber 7, said flap valve as illustrated in Fig. 5, comprising a rectangular body 9 of flexible material, such as leather having a central rectangular flap 9^a cut therein, said flap being of slightly greater area than the seat about intake passage 7^a.

Flap 9^a preferably has attached thereto a suitable weight 10 which may be of rectangular form and which may be secured to said flap by any suitable means, such as nutted bolt 11, a small pin or rivet 12 also being preferably employed to prevent weight 10 from turning.

As illustrated, the longitudinal edges of the valve body 9 each have a pair of spaced semi-cylindrical recesses 9^b, which recesses are adapted to be vertically aligned with bolt holes formed in the laterally projecting bulges or ears 6^c of chamber 6. Vertical bolts

13 extend through said bolt holes engaging the recessed portions of the valve body 9 and threadedly engaging the bottom portion of the intake chamber 7, thereby clamping chamber 7 tightly against the adjacent end of chamber 6 with the valve interposed therebetween and with the flap valve 9^a normally covering the seat about the passage 7^a.

The outer end of intake passage 7 may be provided with a plurality of bosses 7^c, any one of which may be drilled or apertured and threaded to

receive an intake conduit 14. The opposite or outlet end of chamber 6 is provided with a substantially rectangular slightly restricted outlet opening 6^a substantially similar in shape and construction to the outlet opening 7^a of valve chamber 7, and a second valve body 9 having the flap valve 9^a formed therein, identical with the flap valve first described is interposed between said outlet end of chamber 6 and the adjacent end of outlet chamber 8. Outlet chamber 8 is provided with laterally extending bulges or ears 8^a having the vertical bolt holes therethrough aligned with the semi-cylindrical recesses 9^b of the outlet flap valve and vertical bolts 13 extend through said bolt holes and threadedly engage the slightly thickened portion of the base of chamber 6 at their inner ends, thereby clamping outlet chamber 8 to the outlet end of chamber 6 with the discharge flap valve 9^a disposed for operation against the rectangular seat or flange about the passage 6^a. Outlet chamber 8, like intake chamber 7, may have a plurality of bosses 8^c disposed at its outer sides and any one of said bosses may be drilled or apertured and threaded to receive a suitable outlet conduit 15.

The top of chamber 6 is provided with an upstanding boss 16 which is threaded to form a vertical passage 16^a communicating centrally with the top of the central chamber 6 and the boss 16 is farther drilled or apertured at its upper end to leave a shoulder or seat 16^b about passage 16^a and a pump cylinder 17 has externally threaded engagement at its inner and lower end with boss 16. A gasket 18 is preferably interposed between the lower extremity of pump cylinder 17 and seat 16^b. A piston 19 is slidably mounted within pump cylinder 17 carrying two or more cup leathers 19^a, which snugly fit within said cylinder. A piston rod 20 is connected at its lower and inner end with piston 19 and works through a bearing in a suitable cap member 21, which may be threadedly secured to the upper end of cylinder 17.

It will be noticed that the bottom of the chamber 6 is slightly inclined so that the water and material passing through the pump in the direction of the arrows will drop slightly as it enters the outlet passage 8 from chamber 6 and also that the edge of the leather bodies 9 of the valve immediately adjacent the free edge of the flaps are rounded or beveled in order that ledges will not be formed to collect material.

The operation of my improved pump may be briefly described as follows:—

The plunger or piston 19 is reciprocated by any suitable means or pump jack and upon the upward stroke a strong suction will be produced in chamber 6 forcing the outlet valve flap 9^a against its flange or seat about outlet passage 6^a and simultaneously causing the intake flap valve 9^a to be opened and liquid to

pass into the chamber 6. Upon the downward stroke of piston 19 pressure is placed upon the liquid in chamber 6 immediately causing the diagonal intake flap valve 9^a to be forced against its seat in closed position and forcing the liquid through the outlet flap valve 9^a into outlet chamber 8 and out of the pump. The weights 10 on the flap valves give additional rigidity to the portion of the flap constituting the closure and make the valves quickly responsive to the action of the piston. Pump cylinder 17 being vertically disposed above the chamber 6 prevents any foreign material from entering the pump cylinder and contacting the plunger or cup leathers.

It will be seen that liquid containing large portions of foreign material, such as rubbish, gravel or mud will readily pass through the pump without impedance, the flap valves when open permitting an unobstructive passage, and the bottom surface of the intake chamber and pumping chamber 6 being inclined slightly toward the delivery end of the pump, thereby permitting the liquid and material to drop slightly when entering the suction chambers and also facilitating the simplicity of the seats for the two valves. No ledges or impediments exist in my structure and it is impossible for sand or rubbish entering the pump to damage the flap valves or to gain access into the pumping cylinder.

It will readily be seen that to inspect the three chambers of the pump or to replace or repair the flap valves, it is only necessary to remove the bolts 13 which clamp the sections together and which clamp the valve bodies between two abutting sections. The structure is exceedingly simple, but will withstand heavy usage and will not be effected by the presence of alkali, acid and mineral in the liquid.

From the foregoing description it will be seen that I have invented a highly efficient force pump especially adapted to be used in pumping liquid containing impurities and foreign material.

The edges of the flap valve bodies 9, it will be seen, constitute an efficient gasket sealing the joints between the pumping chamber 6 and the intake and outlet chambers.

It will, of course, be understood that various changes may be made in the form, details, arrangement and proportions of the parts without departing from the scope of applicant's invention.

What is claimed is:

1. A pump especially adapted for pumping liquid containing foreign material, comprising a horizontal pumping chamber having a substantially straight longitudinal passage therethrough, the bottom of said passage being flat and unobstructed, said passage having an intake port at one end thereof disposed slightly above the bottom of said passage and having an outlet port at the opposite end.

having its lower edge disposed flush with the bottom of said passage, a pumping cylinder communicating laterally with the upper and intermediate portion of said pumping chamber, a reciprocating plunger in said cylinder, a flap valve at the intake end of said pumping chamber having its lower edge free for movement into said passage, and a flap valve at the outlet end of said chamber having its lower edge free for movement outwardly of said passage.

2. A pump especially adapted for pumping liquid containing foreign material, comprising a horizontal pumping chamber having a substantially straight longitudinal passage therethrough, the bottom of said passage being substantially flat and unobstructed, said passage having an intake port at one end thereof disposed slightly above the bottom of said passage and having an outlet port at the opposite end the lower edge of which is disposed flush with the bottom of said passage, a pumping cylinder communicating laterally with the upper and intermediate portion of said pumping chamber, a reciprocating plunger in said cylinder, means for limiting the stroke of said plunger to prevent its projection into said pumping chamber, an intake chamber secured to the intake end of said pumping chamber, an inclined flap valve interposed between said intake chamber and said pumping chamber and having its lower edge free for movement into said passage, an outlet chamber secured to the opposite end of said pumping chamber having a bottom disposed slightly below the level of the lower edge of said outlet port and an inclined flap valve disposed between said pumping chamber and said outlet chamber and having its lower edge free for movement into said outlet chamber.

In testimony whereof I affix my signature.
FREDERICK W. JOHNSON.
